UNITED STATES PATENT OFFICE.

PHILIP R. HATTON, OF LEBANON, NEW HAMPSHIRE, ASSIGNOR TO THE LEBANON MACHINE CO. INC., OF LEBANON, NEW HAMPSHIRE.

TRAFFIC SIGNAL.

Application filed September 11, 1923. Serial No. 662,070.

To all whom it may concern:

Be it known that I, PHILIP R. HATTON, a citizen of the United States, residing at Lebanon, in the county of Grafton and State 5 of New Hampshire, have invented certain new and useful Improvements in Traffic Signals, of which the following is a specification.

This invention relates to traffic signals 10 and especially to that type which is set on the pavement in the center of street intersections for guidance of traffic. It is a purpose of the invention to provide a device which will be cheap to manufacture, yet 15 durable and efficient in operation. A still further purpose is to provide a device of flexible form which will automatically right itself in the event of collision by vehicular traffic. It is also an aim to provide a signal 20 device embodying a special feature whereby the light element is protected against jolts and jars, such as produced when struck by a vehicle, and will be ward- 25 ed from the path of a wheel if directed toward the light.

Additional objects, advantages and features of invention may reside in the construction, arrangement and combination of parts as may become apparent from the following description and drawings, wherein,

Figure 1 is an elevational view of my signal in use,

Fig. 2 is a fragmentary sectional view thereof, enlarged,

Fig. 3 is a top view of the guard element,

Fig. 4 is a fragmentary sectional view of a modified form of signal,

Fig. 5 is a sectional view of a modified form of base element for the signal,

Fig. 6 is a modification of the guard element and its mounting.

There is illustrated in Figs. 1, 2, and 3, a traffic signal including a circular base 10 which is preferably of cast iron, having a 45 convex upper side 11. Centrally through this base an opening 12 is formed in which there is securely held by a screw 13, a light standard 14. In the present instance, this standard is in the form of a resilient flexible 50 coiled-metal tube, and carries at its upper part an electric light lamp socket 15. Secured within the lamp socket, an electric light bulb 16 is shown, which may be energized by means of the wires 17 extending 55 downwardly through the tube or standard

14 to a suitable source of current. A wire guard element 18 is shown protecting the bulb and carried upon the lamp socket in any approved manner. At a suitable point upon the standard 14, but preferably near 60 the lamp socket, a buffer element 19 is mounted. The buffer 19 in the present instance is shown as an annular ring having four radial arms 20 and hub element 21, the hub having an aperture 22 of a size to 65 receive slidably therethrough the standard 14. A set screw 23 is provided extending through the hub to impinge upon the standard for positive retention of the buffer upon the standard. By this arrangement, it will 70 be seen that the buffer may be adjusted variously upon the standard to suit different needs and occasions. The rim 19 may be of rubber or rubber-faced, if desired.

In the use of this device, it will be seen 75 that should the driver of a car fail to judge his distance properly, or by any cause run upon the base, even though the wheel may approach in line with the standard 14, the wheel will strike the buffer 19 pushing the 80 electric bulb and standard to one side, allowing the wheel to pass freely, after which the standard will swing back into erect position for proper display of the signal.

It is important to note that the rim 19 85 is of a diameter quite substantial as compared to that of the wheels of motor vehicles as now ordinarily constructed, and sufficient to cause it to engage both the felly and the spokes near the hub of a wheel, or 90 across two spokes or against the recessed disc of a wheel in such manner as to hold the light safe against being struck by the projecting hub or other wheel parts. If the rim 19 were of small diameter, it might 95 swing between the spokes or between the felly and hub in such manner that the light would be directly struck by parts of the wheel. The buffer 19 is adjusted preferably at a height to lie just below the hub caps 100 of the smaller wheels of vehicles, and it will then be in position above running boards, so that it will guard the light against being struck by the lower parts of fenders adjacent the running boards. 105

In Fig. 4, I have illustrated a construction of signal employing a liquid fuel as the light source. Here the base 24 is in outward appearance, similar to that described in connection with Figs. 1 and 2, but has 110

formed in the center thereof, a reservoir 25, a filling opening 26 being shown upon the upper side, closed by a cap 27. Centrally through the top of the base, an opening 28 is formed in which there is securely held a small flexible metal tubing 29 through which a wick element 30 is extended down into the reservoir 25. Circumscribing the opening 28, there is a larger opening 31 in which a resilient flexible metal standard 32 of similar construction to that previously described, is mounted, carrying at its upper end a suitable form of lamp 33 and protecting guard 34. A buffer 19 is shown, also, operating in the manner before described.

In the event that a rigid standard is desired, this may be effected as shown in Fig. 5, and still retain the swinging motion of the signal, whereby the lamp element may be swung outwardly of the path of a vehicle. In this construction the base has a hollow interior 35. The upper face of the base is suitably apertured and cupped for reception of a ball joint 37 of a rigid standard 38, having a stem 36 projecting within the base. A cap element 39 may be fitted down over the ball 37 and suitably fastened to the base, the cap being sufficiently open at the top to permit free swinging movement of the signal, in any direction, the direction of movement of the signal depending upon the angle at which the signal is struck by a vehicle. A short distance below the ball 37 a counterweight element 40 is formed upon the stem 36 and to the element 40 one end of each of four or more radial springs 41 are secured; the opposite ends being secured to eye members 42 on the interior 35 of the base. The standard 38 is hollow throughout its length so that electrical wires 43 may be threaded therethrough.

In Fig. 6, I have shown a further form of buffer whereby the filament of an electric light may be saved severe jolts due to collisions. An oscillatable standard 44 of any suitable construction is shown carrying a lamp mounting 45 as before. The buffer element 46, however, is shown as a hoop element encircling the standard and without any rigid connection thereto, being supported by sets of spring elements 47 from above and below, respectively, extending

from the hoop to the standard. With this device in operation, when the buffer element is struck, the hoop element will tend to move away from the object striking the signal and motion gradually imparted to the light through the springs; and not until after the part of the movement of the hoop has occurred will full movement of the light occur with the standard.

I claim:

1. In a device of the character described, a base, a light element, an oscillatable mounting therefor, extending upwardly from the base, and an encircling member carried by the mounting spaced a distance above the base lying below the light and projecting a distance therebeyond horizontally, for the purposes described, said encircling member comprising an annular rim, a hub part adjustable vertically on the mounting, and connecting parts between rim and hub.

2. The structure recited in claim 1 in which the annular rim is of a size to so engage between felly and spokes or across spokes of a vehicle wheel as to hold the light element clear of wheel parts.

3. A lamp structure comprising a reservoir base element, a flexible coiled-metal wick holder leading upward from the reservoir, a burner at the upper end of the wick holder, a wick carried by said burner and extending through the wick holder to the reservoir, and an outer resilient coiled metal member fixed on the burner around the wick holder and separately connected to said base.

4. In a device of the character described, a flexible resilient standard, a lighting device mounted on the upper end thereof, and a guard device adjustable on the standard including an annular buffer part and having a hub slidable on the standard and means to fix the hub in adjusted positions; said annular buffer part being of substantial diameter as compared to the wheels of vehicles whereby it will be warded outward by engagement across spokes and across felly and spoke as indicated.

In testimony whereof I have affixed my signature.

PHILIP R. HATTON.
